(57) **CLAIM**

The ornamental design for an adapter used with an accessory-host interface, as shown and described.

DESCRIPTION

FIG. 1 is a front perspective view of a first embodiment showing the plug end of an adapter used with an accessory-host interface disposed in a host device;

FIG. 2 is a reverse perspective view of a first embodiment showing the receptacle end of the adapter used with an accessory-host interface;

FIG. 3 is a top plan view of a first embodiment of the adapter used with an accessory-host interface;

FIG. 4 is a left side elevation view of a first embodiment of the adapter used with an accessory-host interface;

FIG. 5 is a bottom plan view of a first embodiment of the adapter used with an accessory-host interface;

FIG. 6 is a right side elevation view of a first embodiment of the adapter used with an accessory-host interface;

FIG. 7 is a front elevation view of a first embodiment of the adapter used with an accessory-host interface;

FIG. 8 is a reverse elevation view of a first embodiment of the adapter used with an accessory-host interface;

FIG. 66 is a reverse perspective view of a ninth embodiment showing the receptacle end of the adapter used with an accessory-host interface;

FIG. 67 is a top plan view of a ninth embodiment of the adapter used with an accessory-host interface;

FIG. 68 is a left side elevation view of a ninth embodiment of the adapter used with an accessory-host interface;

FIG. 69 is a bottom plan view of a ninth embodiment of the adapter used with an accessory-host interface;

FIG. 70 is a right side elevation view of a ninth embodiment of the adapter used with an accessory-host interface;

FIG. 71 is a front elevation view of a ninth embodiment of the adapter used with an accessory-host interface;

FIG. 72 is a reverse elevation view of a ninth embodiment of the adapter used with an accessory-host interface;

FIG. 73 is a front perspective view of a tenth embodiment showing the plug end of an adapter used with an accessory-host interface disposed in a host device;

FIG. 74 is a reverse perspective view of a tenth embodiment showing the receptacle end of the adapter used with an accessory-host interface;

FIG. 75 is a top plan view of a tenth embodiment of the adapter used with an accessory-host interface;

FIG. 76 is a left side elevation view of a tenth embodiment of the adapter used with an accessory-host interface;

FIG. 77 is a bottom plan view of a tenth embodiment of the adapter used with an accessory-host interface;

FIG. 78 is a right side elevation view of a tenth embodiment of the adapter used with an accessory-host interface;

FIG. 79 is a front elevation view of a tenth embodiment of the adapter used with an accessory-host interface;

FIG. 80 is a reverse elevation view of a tenth embodiment of the adapter used with an accessory-host interface;

FIG. 81 is a front perspective view of an eleventh embodiment showing the plug end of an adapter used with an accessory-host interface disposed in a host device;

FIG. 82 is a reverse perspective view of an eleventh embodiment showing the receptacle end of the adapter used with an accessory-host interface;

FIG. 83 is a top plan view of an eleventh embodiment of the adapter used with an accessory-host interface;

FIG. 84 is a left side elevation view of an eleventh embodiment of the adapter used with an accessory-host interface;

FIG. 85 is a bottom plan view of an eleventh embodiment of the adapter used with an accessory-host interface;

FIG. 86 is a right side elevation view of an eleventh embodiment of the adapter used with an accessory-host interface;

FIG. 87 is a front elevation view of an eleventh embodiment of the adapter used with an accessory-host interface;

FIG. 88 is a reverse elevation view of an eleventh embodiment of the adapter used with an accessory-host interface;

FIG. 89 is a front perspective view of a twelfth embodiment showing the plug end of an adapter used with an accessory-host interface disposed in a host device;

FIG. 90 is a reverse perspective view of a twelfth embodiment showing the receptacle end of the adapter used with an accessory-host interface;

FIG. 91 is a top plan view of a twelfth embodiment of the adapter used with an accessory-host interface;

FIG. 92 is a left side elevation view of a twelfth embodiment of the adapter used with an accessory-host interface;

FIG. 93 is a bottom plan view of a twelfth embodiment of the adapter used with an accessory-host interface;

FIG. 94 is a right side elevation view of a twelfth embodiment of the adapter used with an accessory-host interface;

FIG. 95 is a front elevation view of a twelfth embodiment of the adapter used with an accessory-host interface;

FIG. 96 is a reverse elevation view of a twelfth embodiment of the adapter used with an accessory-host interface;

FIG. 97 is a front perspective view of a thirteenth embodiment showing the plug end of an adapter used with an accessory-host interface disposed in a host device;

FIG. 98 is a reverse perspective view of a thirteenth embodiment showing the receptacle end of the adapter used with an accessory-host interface;

FIG. 99 is a top plan view of a thirteenth embodiment of the adapter used with an accessory-host interface;

FIG. 100 is a left side elevation view of a thirteenth embodiment of the adapter used with an accessory-host interface;

FIG. 101 is a bottom plan view of a thirteenth embodiment of the adapter used with an accessory-host interface;

FIG. 102 is a right side elevation view of a thirteenth embodiment of the adapter used with an accessory-host interface;

FIG. 103 is a front elevation view of a thirteenth embodiment of the adapter used with an accessory-host interface;

FIG. 104 is a reverse elevation view of a thirteenth embodiment of the adapter used with an accessory-host interface;

FIG. 105 is a front perspective view of a fourteenth embodiment showing the plug end of an adapter used with an accessory-host interface disposed in a host device;

FIG. 106 is a reverse perspective view of a fourteenth embodiment showing the receptacle end of the adapter used with an accessory-host interface;

FIG. 107 is a top plan view of a fourteenth embodiment of the adapter used with an accessory-host interface;

FIG. 108 is a left side elevation view of a fourteenth embodiment of the adapter used with an accessory-host interface;

FIG. 109 is a bottom plan view of a fourteenth embodiment of the adapter used with an accessory-host interface;

FIG. 110 is a right side elevation view of a fourteenth embodiment of the adapter used with an accessory-host interface;

FIG. 111 is a front elevation view of a fourteenth embodiment of the adapter used with an accessory-host interface;

FIG. 112 is a reverse elevation view of a fourteenth embodiment of the adapter used with an accessory-host interface;

FIG. 113 is a front perspective view of a fifteenth embodiment showing the plug end of an adapter used with an accessory-host interface disposed in a host device;

FIG. 114 is a reverse perspective view of a fifteenth embodiment showing the receptacle end of the adapter used with an accessory-host interface;

FIG. 115 is a top plan view of a fifteenth embodiment of the adapter used with an accessory-host interface;

FIG. 116 is a left side elevation view of a fifteenth embodiment of the adapter used with an accessory-host interface;

FIG. 117 is a bottom plan view of a fifteenth embodiment of the adapter used with an accessory-host interface;

FIG. 118 is a right side elevation view of a fifteenth embodiment of the adapter used with an accessory-host interface;

FIG. 119 is a front elevation view of a fifteenth embodiment of the adapter used with an accessory-host interface; and,

FIG. 120 is a reverse elevation view of a fifteenth embodiment of the adapter used with an accessory-host interface.

The broken lines in the drawings illustrate unclaimed portions of the adapter used with an accessory-host interface and form no part of the claimed invention.
